AUTOMATIC ALARM-VALVE.

1,125,407.

Specification of Letters Patent.

Patented Jan. 19, 1915.

Application filed May 2, 1903. Serial No. 155,323.

To all whom it may concern:

Be it known that I, EDWARD F. SHIPMAN, a citizen of the United States, and a resident of the city of New York, borough of Brooklyn, in the county of Kings and State of New York, have invented a new and Improved Automatic Alarm-Valve, of which the following is a full, clear, and exact description.

My invention relates to improvements in automatic alarm valves, designed especially for use in fire extinguisher systems of that class wherein a supply of water is maintained in distributing pipes, for instant out-flow from the sprinkler distributing system on the opening of any of the numerous sprinkler heads arranged thereon.

One object of this invention is the provision of means by which the pulsation of a column of water, commonly known as "water hammer", is absorbed or taken up in such a way as to prevent disturbance of the main valve on its seat; such means also making provision for the flow of a limited volume of water around the main valve due to leakage in the system or the opening of one of the sprinkler heads, said limited flow being insufficient to establish such a difference in pressure on the respective sides of the main valve as to cause the opening thereof.

A further object is to associate with the by-pass a suitable form of signal actuating device which is controllable by the flow of water through said by-pass to give an audible signal in the event of continued or uninterrupted flow of water through the by-pass, but this signal actuating device does not respond to such pulsations of water known as "water hammer".

A further object is to provide a novel form of signal actuating device controllable by the opening of the main valve.

Further objects and advantages of the invention will appear in the course of the subjoined description, and the novelty will be defined by the annexed claims.

Reference is to be had to the accompanying drawings forming a part of this specification, in which similar characters of reference indicate corresponding parts in all the figures.

Figure 1 is a sectional elevation illustrating a stand-pipe of a fire extinguisher system with my improvements applied thereto; Fig. 2 is an enlarged vertical sectional ele-

vation through a portion of the by-pass pipe and the diaphragm governor associated therewith; Fig. 3 is a sectional elevation of one form of signal actuating device which is controllable by the opening of the main valve; Fig. 4 is a sectional elevation of a modified form of diaphragm governor, illustrating another type of dash pot mechanism to retard the movement of the diaphragm stem in one direction; Fig. 5 is a sectional elevation of another type of governor controllable by the by-pass; Fig. 6 is an enlarged detail view through a valved piston employed in the construction shown by Fig. 5; and Fig. 7 is a sectional elevation of another type of signal actuating device and governor adapted for use in connection with the by-pass. Fig. 8 is a vertical section through another form of governor employing valves instead of a diaphragm.

5 designates a stand-pipe forming a part of an ordinary fire extinguisher system, and in this stand-pipe is interposed a valve casting or shell 6, the latter being provided with an inclined recess 7, in which is secured a ring or annulus 8, adapted to form the seat of a main valve 9. This ring or annulus is provided with an air chamber 10, which extends continuously around said ring, and the upper side or face of the valve seat ring 75 is formed with a plurality of apertures 11 which communicate with the chamber 10 and open through the upper face of the valve seat. The chamber 10 of the valve seat ring is open to communication with the 80 surrounding atmosphere by means of a port 12, having communication with a pipe 13, which will be hereinafter described.

The valve 9 is of the hinged variety, although this is not essential, and said valve 95 is attached by a bolt 14 to an arm 15, which is hinged at 16 in the valve casing 6, whereby the valve is movable toward and from the annular seat ring 8. The valve is provided on its face with a packing 17 of any 100 suitable material, and in this packing is formed an annular groove or channel 18, arranged to have communication with the series of ports 11 and with the air chamber 10 when the valve is closed to the position 105 shown by Fig. 1, whereby the under face of the valve is exposed to atmospheric pressure. The valve 9 is practically a differential valve, and it is held or pressed normally to its seat by the pressure of the water in the 110

pipe 5, even though the water pressure in the pipe above the valve is lower than the pressure in the pipe below the valve. It is well known to those skilled in the art that differential valves used in fire extinguisher systems are held in their closed positions by the pressure of water within certain limits. This water pressure in different systems may vary, but it is common to use water at one hundred pounds pressure. This pressure of one hundred pounds is normally maintained on the under face of the differential valve, but the pressure on the upper face of the valve may vary within certain limits; that is to say, the pressure above the valve due to leakage in the system may be reduced a few pounds under the pressure on the lower side of the valve without opening said valve.

In my system I employ a by-pass which has communication with the stand-pipe on opposite sides of the differential main valve. This by-pass is shown by Fig. 1 as consisting of a pipe 19 made in suitable lengths, and having branches connected either with the stand-pipe 5 or with the valve casing 6, at points above and below said main valve 9. As indicated in Fig. 8 the by-pass may in some cases be provided in its upper branch with a check valve 20, having communication with the stand-pipe at a point above the main valve 9, said check valve being arranged to open freely in one direction for the passage of the water from the by-pass into the stand-pipe, but it closes in an opposite direction so as to prevent water from passing back from the stand-pipe into the by-pass pipe, as will be readily understood.

The opening of the main valve 9 is the occasion for sounding an audible alarm, and this alarm mechanism is actuated by fluid pressure signal actuating devices. The audible alarm is represented by the drawings in the form of an electric bell 21, which is included in an electric circuit 22 having a battery 23 or other source of electrical energy. In the drawings I have shown different forms of signal or alarm devices, one of which is the electric bell 21, and another is embodied in the form of a pneumatic whistle 24, but it will be understood that I do not limit myself to these two forms of alarm, but may instead employ any fair equivalent therefor.

The electric circuit 22 has separate contacts 25, which are disposed in the upper portion of an extension 26 of a trap consisting of legs 27, 28, the last-named leg being provided with a pipe extension 29 which is united by a coupling 30 and a pipe 31 to the air passage 12 leading to the chamber of the annular valve seat 8. The legs 27, 28 of the trap are filled with mercury or its equivalent up to the level indicated in Fig. 3, and when the valve 9 is open the water is free to pass through the

valve casing 6 and the stand-pipe 5. The water also flows through the ports 11 of the annular valve seat, into the chamber 10, through the passage 12 and the pipes 31, 29, so as to exert pressure on the column of mercury contained in the legs 28, 27 of the trap, thereby displacing the mercury and forcing the same into the extension 26 of the trap until the circuit contacts 25 are immersed in the mercury, thereby closing the normally open circuit 22 for the operation of the bell 21. When the valve 9 is again closed, the water contained in the pipes 31, 29 is displaced by the backward flow of the mercury, the latter returning by gravity to the legs 27, 28. The water is free to escape through the pipe 13, which is coupled by the union 30 to the pipes 29, 31, thus withdrawing the mercury from the contacts 25 and opening the circuit 22 to stop the alarm.

It is desirable to prevent the too rapid upward movement of the column of mercury in the trap when acted on by the flow of water from the valve casing on the opening of the main valve, and I provide a checking device in the trap for this purpose. Between the leg 27 of the trap and the pipe extension 26, I employ a valve casing 36 having a valve seat 37, against which bears a valve 38. This valve 38 is provided with a contracted port 39, of small area, and on the upper side of the valve is a deflector 40, which lies immediately over the contracted port 39, for the purpose of preventing a jet of mercury from being projected through said port in the valve and impinging the contacts 25, thus overcoming premature closing of the circuit 22. The valve 38 is normally held to its seat by any suitable form of retractor, such as the coiled spring 41, reference being had to Fig. 3. When the column of mercury in the trap is displaced by the upward flow of water through the pipe 29 supplied from the hollow valve seat in the stand-pipe, the mercury fills the valve chamber 36 and flows in a limited quantity through the contracted port 39 of said valve. The mercury gradually accumulates in the pipe 26 until its level reaches the contacts 25 for the purpose of closing the circuit, thus giving the alarm when the main valve is opened as has been described; but when the water pressure in the trap is reduced, the mercury flows by gravity from the pipe 26 back into the trap, the weight of the mercury serving to displace the valve 38 from its seat and thereby open said valve so as to insure a quick return of the mercury by gravity to the trap.

The signal 24 has an air pipe 32 coupled thereto, said pipe being attached to an air compressor tank 33, which is adapted to be supplied with water by a pipe 34 having a bell mouth 35, into which extends the lower extremity of the pipe 13. On the opening

of the main valve 9 and the flow of water through the valve seat ring 8 and pipe 31 to the pipe extension 28 of the trap, some of the water will flow through the pipe 18 into the pipe 34 and entrain into said pipe. The air enters the tank 33 along with the water, and the accumulation of water operates to compress air in said tank sufficiently to sound the pneumatic whistle 24. It will be understood that one or the other of these signal devices associated with the main valve may be omitted.

It will be observed from the foregoing description that the by-pass is provided with a check valve 20 which allows the water to pass from said by-pass into the stand-pipe at a point above the valve 9 in case of a sudden rise of pressure, thus equalizing the pressure on each side of the main valve. When the increased pressure is due to "water hammer," an excess of pressure will be formed on the upper face of the main valve, because the water from the lower part of the stand-pipe will take the path of least resistance, which is through the by-pass and around the main valve, thereby holding the main valve more tightly to its seat, the small check valve preventing the return of the water through the by-pass.

The employment of the perforations 11 in the face of the annular valve-seat is advantageous because they serve as a screen for the main outlet. The combined area of the openings 11 more than equals the area of the large opening, so that it is not possible for sediment to clog up the discharge opening. The groove 18 in the packing 17 of the main valve covers the perforations 11 in the valve seat, and as this groove 18 is on the moving part of the valve it will be understood that said grooved part moves upwardly with the valve when the latter is open, thus exposing the grooved face of the valve and the perforated face of the valve seat to the flow of water, which flushes these parts clean of any sediment, thus making it impossible for sediment to clog up the discharge pipes and render the valve inoperative.

One of the important features of my invention resides in the employment of a signal-actuating mechanism which is controllable by the flow of water through the by-pass 19, but this signal actuating mechanism does not respond to the pulsations of the water column in the stand-pipe 5 due to the action of the "water hammer."

One form of the signal-actuating mechanism is represented by Figs. 1 and 2 of the drawings, wherein I employ a governor having a double diaphragm. One of the diaphragms 42 is contained within a casing 43 having a pipe 44 which is connected directly to the by-pass pipe 19. The other diaphragm 45 is confined in a similar casing

46, which has communication by a pipe 47 with the by-pass pipe 19. The pipe 44 conveys water from the by-pass to the under side of the lower diaphragm 42, while the other pipe 47 supplies water from the by-pass to the upper side of the upper diaphragm 45. (see Fig. 2). The two diaphragms 42, 45 are connected operatively by a stem 48, which spans the space between the diaphragm chambers 43, 46, so as to insure simultaneous movement of the two diaphragms, and this diaphragm stem in one embodiment of the invention serves as the means for closing the electric circuit 22. One of the diaphragm casings, preferably the casing 46, is provided with circuit contacts 49, which are connected in multiple at 50 in the electric circuit 22, and these contacts 49 are insulated from the casing 46 and disposed in the path of a contact 51 on the diaphragm stem 48, the parts 49, 51 constituting practically a circuit closer.

The by-pass 19 is provided with means whereby the flow of water therethrough will establish a difference in pressure on the diaphragms 42, 45, and in one embodiment of the invention I contemplate the employment of an ejector having a suction side connected with the upper diaphragm chamber, and also having communication through the by-pass with the lower portion of the diaphragm chamber 43. This ejector is shown by Fig. 2 in the form of two nozzles 52, 53, which are contained in a suitable casing 54 that is interposed in the by-pass 19 near the upper part thereof. The nozzle 52 is attached to the lower part of the casing 54 to have communication through the lower part of the by-pass directly with the lower diaphragm casing 43 at a point below the lower diaphragm, while the upper nozzle 53 is disposed in the casing 54 for communication uninterruptedly with the stand-pipe 5 at a point above said main valve. The nozzles 52, 53 are tapered and disposed in reverse positions, and these nozzles are furthermore arranged to have their contracted ends separated a short distance by a space which communicates with the pipe 47 that couples the upper diaphragm casing to the by-pass.

To prevent the signal-actuating mechanism from responding to the pulsations of water in the stand-pipe and by-pass by the "water-hammer," I associate a checking or retarding fluid pressure device with the diaphragm governor mechanism. This checking or retarding device is represented in the form of a dash pot 55, having a restricted port 56 in its bottom, said dash pot and the upper part of the diaphragm chamber 43 being partially filled with any suitable fluid, such as oil. The bottom of the dash pot 55 is also provided with a port 57, of larger area than the port 56, and this port 57 is normally closed by a check valve 58 which

is adapted to open downwardly and provide for the backward flow of liquid from the dash pot into the upper part of the diaphragm chamber 43. The by-pass 19 provides for the flow of water around the main valve to compensate for leakage in the stand-pipe, and for the passage of water in case one of the sprinkler heads opens. The opening of one sprinkler head will establish a difference in pressure in the stand-pipe on opposite sides of the valve less than the difference required to open the main valve, and the flow of water will take place continuously or interruptedly through the by-pass 19. Under these conditions the flow of water through the by-pass and the nozzles 52, 53, will create a suction through the pipe 47 from the upper side of the diaphragm 45, whereas the lower diaphragm 42 will be exposed to the pressure of the water in the by-pass 19 and the pipe 44. The difference in the pressure on the upper and lower diaphragms 42, 45, permits the stem 48 to be raised until the circuit closer 51 engages the contacts 49 and thereby closes the circuit 22 for the purpose of sounding the alarm 21, this operation taking place before the main valve 9 opens. The upward movement of the stem 48 takes place quite slowly, owing to the fact that the liquid of the dash pot must flow through the contracted port 56 from the chamber above the diaphragm 42 into the chamber of the dash pot 55, but the continued application of pressure from the by-pass and through the pipe 44 on the under side of the diaphragm 42, together with a reduction of pressure on the upper side of the diaphragm 45, will displace the oil from the chamber above the diaphragm 42 into the dash pot, so that the stem 48 will be gradually lifted for the closer 51 to engage the contacts 49. The presence of the oil in the dash pot and above the diaphragm 42 prevents the pulsation of water due to water-hammer from influencing the stem 48 to such an extent as to close the circuit. The release of pressure on the under side of the diaphragm 42, or the reestablishment of equal pressure on the diaphragms 42, 45 (by the return of the other parts to normal position) allows the valve 58 to open and permit the comparatively quick return of the oil from the dash pot into the chamber above the diaphragm 42.

In the embodiment of the invention shown by Fig. 4, the signal-controlling device retains the generic features of the invention shown by Figs. 1 and 2, except that the form of the circuit closer and the construction of the dash pot is changed somewhat. Instead of placing the circuit closer directly on the diaphragm stem 48, I employ a lever 60 fulcrumed at one end on a post 61 fixed to the lower diaphragm casing 43. This lever is pivoted at a point intermediate of its length at 62 on the stem 48, and at its free end said lever is equipped with a circuit closer contact 51^a adapted to engage the circuit terminals 49^a which are included in the electric circuit 22. The dash pot 63 is mounted on the lower diaphragm casing 43, but it does not have communication therewith. In this dash pot is arranged a valved piston 64, an enlarged detail view of which is represented by Fig. 6. This piston is provided with a chamber 65, and at the top and bottom of the piston are provided ports 66. In the piston is a partition 67, having a port 68, adapted to be closed by means of a valve 69, having a contracted port 70. The piston 64 is connected with the lever 60 by a piston rod 71, and the chamber of the dash pot 63 is filled with liquid such as oil. This dash pot serves to check or retard the upward movement of the lever 60 and the diaphragm stem 48, because the liquid must flow through the restricted opening 70 of the valve 69 when the stem 48 is lifted by pressure against the under side of the diaphragm 42, but when this pressure is relieved, the stem 48, lever 60 and piston rod 71 are adapted to move toward their normal positions with comparative freedom, because the valve 69 will be displaced from its seat when the piston 64 moves in a downward direction.

In the form of construction shown by Fig. 5, I dispense with the diaphragm governor as a means for controlling the signal when water passes through the by-pass, and substitute therefor a fluid pressure governor of another form. This governor consists of a cylinder 72, having a pipe 73 which connects its lower portion to the by-pass 19. The cylinder is also provided at a point intermediate of its length with a pipe 74, which connects the same with the upper portion of said by-pass, and the upper portion of this cylinder is enlarged to form a receiver 75, in which are arranged the circuit terminals 49^b of the electric signal circuit 22. The cylinder 72 is designed to be filled with water to a level above the pipe 74, and the upper part of said cylinder, together with the receiver 75, is charged with a non-conducting liquid consisting preferably of oil of a suitable nature. In the cylinder 72 is a reciprocating plunger 76, having an upstanding stem 77 which is provided at its upper extremity with a circuit-closing contact 78. The stem 77 is also equipped with a valved plunger 79, which is similar in construction to the piston 64 of the dash pot, the detailed construction of said piston 64 being shown by Fig. 6. This plunger or piston 79 is made fast with the rod 77, which connects it to the piston 76, so that the parts 76, 79 will move simultaneously with the contact 78. Normally

the parts occupy the lowered position shown by Fig. 5 when normal conditions prevail in the by-pass and the main valve is closed, but the flow of water through the by-pass by the opening of one of the sprinkler heads, or by leakage through the system, will cause the pistons 76, 79 to rise, thereby moving, within certain restrictions, the contact 78 into engagement with the circuit terminals 49^c for the purpose of closing the circuit 22 and giving the alarm. The employment of the valved plunger 79 insures the slow upward movement of the plungers and piston rod under the increased pressure of water flowing through the by-pass, and the valved plunger 79 prevents an abnormal movement of the parts forming the signal-actuating mechanism under the pulsations of the column of water due to the water-hammer action.

The modification represented by Fig. 7 is somewhat analogous to the construction of Fig. 5, in that it employs a liquid for closing the circuit through the terminals, but in this form of construction I employ mercury and insulating oil adapted to be displaced by an increase in the water pressure of the by-pass. A mercury receiver 80 is connected at its lower part by a pipe 81, with the corresponding part of the by-pass, and from the upper part of this receiver extends a cylinder 82, which at its upper end communicates with a liquid receiver 83. From the upper part of the by-pass leads a pipe 84, having a water cup 85, from which extends a pipe connection 86 attached to the upper part of the oil receiver 83. In this oil receiver are arranged the circuit terminals 49^c having suitable connection with the electric circuit 22. The communication between the cylinder 82 and the mercury receiver 80 is cut off by a partition 87, and between the upper part of this cylinder 82 and the oil receiver 83 is another partition 88. Extending upwardly from the bottom of the mercury receiver 80 is a pipe 89, having communication with the water pipe 81 and terminating close to the partition 87. A connecting pipe 90 is fixed to the partition 87 for communication with the cylinder 82, and this pipe 90 dips into the mercury contained in the receiver 80, the level of the mercury being normally below the upper extremity of the water inlet pipe 89. The partition 88 is provided with a port 91 adapted to be closed by a valve 92, which is held normally to its seat by a spring 93, and in this valve 92 is a contracted port 94, which permits the oil from the lower part of the cylinder 82 to pass slowly into the oil receiver 83. With the pipes 81, 84, and the water vessel 85 filled with water, an increase in pressure due to the passage of water through the by-pass will force the water from the pipe 81 into the pipe 89, thereby displacing the mercury

contained in the receiver 80 and forcing it through the pipe 90 into the cylinder 82. The ascent of the mercury will displace the oil from the cylinder 82 through the valved port 94, the oil gradually passing by the action of the mercury from the cylinder 82 into the oil receiver 83. The oil is thus displaced from this receiver 83 through the pipe 86 into the water vessel 85, and the continued upward movement of the oil, followed by the strata of mercury and the water, will eventually displace the oil from the receiver 83 and fill the latter with mercury so as to close the circuit by immersing the circuit terminals 49^c in the mercury, the oil making its exit through the pipe 86 into the receiver 85 and the pipe 84. The restoration of normal conditions in the system will cause the water to flow back through the pipe 84 so as to force the mercury and the oil back to the receiver 80 and the cylinder 82 and receiver 83, and during this backward flow of the mercury and oil the valve 92 is displaced so as to permit a comparatively free return of the liquids to their normal condition.

In lieu of the dash pot devices for controlling the regulator of Figs. 1 and 2 against the water hammer, I may use the check valves 93, 94, in the branch pipes 44, 47, as shown in Fig. 8. These check valves are disposed to open in opposite directions to one another, and each valve has a port 95 of small area so as to permit a slow movement of the water in one direction, while the flow of water in the other direction opens the valve to permit a comparatively free flow.

Having thus described my invention, I claim as new and desire to secure by Letters Patent:

1. In automatic sprinkler alarm apparatus, a water supply pipe for an automatic sprinkler system, a main check valve therein, a movable governing body of conducting liquid, an electric alarm mechanism operatively related to said body, an alarm actuating device coöperating with said main valve and operated under emergency conditions in said system to move said body into emergency position and cause it to condition the alarm mechanism to operate, and to tend to restore said body to ineffective position when said system is restored to normal conditions and a uni-directional retarding valve having a restricted retarding passage for retarding the movement of said body toward its emergency position and opening to provide a larger return passage for said body for allowing its relatively free more rapid movement in returning toward its normal ineffective position.

2. In automatic sprinkler alarm apparatus, a water supply pipe for an automatic sprinkler system, a movable governing body of conducting liquid, an alarm mechanism

- 6
- operatively related to said body, an alarm actuating device coöperating with and operated under emergency conditions in said system to move said body into emergency position and cause it to condition the alarm mechanism to operate, and to tend to restore said body to ineffective position when said system is restored to normal conditions and a uni-directional retarding valve for retarding the movement of said body toward its emergency position and opening to provide a larger return passage for said body for allowing its relatively free more rapid movement in returning toward its normal ineffective position.
3. In automatic sprinkler alarm apparatus, a water supply pipe for an automatic sprinkler system, a movable governing body of conducting liquid, an alarm mechanism operatively related to said body, an alarm actuating device coöperating with and operated under emergency conditions in said system to move said body into emergency position and cause it to condition the alarm mechanism to operate, and to tend to restore said body to ineffective position when said system is restored to normal conditions and retarding means for retarding the movement of said body.
4. In an automatic alarm device, the combination with a pipe and a main valve, of a signal, and a signal-actuating means controllable by the movement of said main valve; said means comprising a trap adapted to contain a mercury seal and a valve which restricts the flow of said seal to circuit terminals in one direction, and is effective in permitting the mercury seal to return readily to normal condition in the trap.
5. In an automatic alarm device, the combination with a pipe, and a main valve therein, of a signal, and signal-actuating means controllable by the opening of said main valve for actuating said signal; said means comprising a trap adapted to contain a mercury seal, an extension from said trap containing circuit terminals and a valve provided with a restricted port.
6. In an automatic alarm device, the combination with a supply pipe for a sprinkler system and a main valve therein, of an electric signal, a signal-actuating mechanism including a column of trapped mercury controllable by the flow of water in the system to close a circuit of the electric signal and means to retard the movement of said mercury.
7. In an automatic alarm device, the combination with a pipe, and a main valve therein, and a by-pass communicating with said pipe on opposite sides of the main valve, of signal-actuating devices controllable by the flow of water through said by-pass, and arranged to actuate a signal by 65 the uninterrupted flow of water through
- said by-pass, and checking or retarding means opposing the movement of the signal-actuating mechanism under pulsations in the column of water contained in the by-pass.
8. In an automatic alarm device, the combination with a pipe, and a main valve therein, of a by-pass communicating with said pipe, and a signal-actuating mechanism controllable by the flow of water through said by-pass; said signal-actuating mechanism including separate diaphragms exposed to pressure of water in the by-pass, an ejector device having suction communication with one diaphragm chamber and direct communication through the by-pass with the other diaphragm chamber, and circuit-closing devices actuated by displacement of said diaphragms.
9. In an automatic alarm device, the combination with a by-pass, of separate diaphragm chambers communicating with said by-pass, an ejector nozzle device in said by-pass, connected diaphragms in said chambers, and a circuit-closing device controllable by the movement of said diaphragms.
10. In an automatic alarm device, the combination with a by-pass, of separate diaphragm chambers having communication independently of each other with said by-pass, a nozzle in said by-pass with suction communication to one diaphragm chamber, separate diaphragms in said chambers, a stem connecting the diaphragms, and a circuit-closer controllable by said stem.
11. In an automatic alarm device, the combination of a by-pass, separate diaphragm chambers communicating individually with said by-pass, a nozzle mounted in said by-pass, separate diaphragms mounted within said chambers and connected by an intermediate stem, a dash pot for opposing the movements of said diaphragms, and signal actuating mechanism connected with said by-pass and co-acting therewith.
12. In an automatic alarm device, the combination of a by-pass, connected diaphragms having communication with said by-pass, a nozzle disposed within said by-pass, a valved dash pot operatively connected with said diaphragms and adapted to oppose the movement thereof in one direction and to permit a relatively free movement of the diaphragms in the opposite direction, and signal actuating mechanism connected with said by-pass.
13. In automatic sprinkler alarm apparatus, a water supply pipe for an automatic sprinkler system, a main check valve therein, a movable body of conductive liquid, an electric alarm mechanism operatively related to said body, an alarm actuating device coöperating with said main valve and operated under emergency conditions in said system to move said body into emergency

- position and cause it to condition the alarm mechanism to operate, and to tend to restore said body to ineffective position when said system is restored to normal conditions 5 and unidirectional retarding means for retarding the movement of said body toward its emergency position and for allowing its more rapid movement in returning toward its normal ineffective position.
14. In automatic sprinkler alarm apparatus, a water supply pipe for an automatic sprinkler system, a movable body of liquid, an alarm mechanism operatively related to said body, an alarm actuating device co-operating with and operated under emergency conditions in said system to move said body into emergency position and cause it to condition the alarm mechanism to operate, and to tend to restore said body to ineffective position when said system is restored to normal conditions and retarding means for retarding the movement of said body. 15. In automatic sprinkler alarm apparatus, a water supply pipe for an automatic sprinkler system, a main valve therein, a movable governing body, an alarm mechanism operatively related to said body, an alarm actuating device co-operating with said main valve and operated under emergency conditions in said system to move said body into emergency position and cause it to condition the alarm mechanism to operate, and to tend to restore said body to ineffective position when said system is restored to normal conditions and retarding means for retarding the movement of said body. 16. In an automatic alarm device, a pipe connected to a fire extinguishing system, a signal-actuating mechanism, a signal to be actuated by said mechanism, said signal-actuating mechanism including a trap containing a mercury seal disposed to have access to the terminals of a circuit which includes said signal, and means for restricting the movement of the mercury seal to the circuit terminals. 17. In a device of the class described, the combination with a valve and an alarm mechanism, of a shifting body for conditioning the alarm mechanism to operate, means through which the valve in opening conditions said body to shift, and means for retarding its movement. 18. In a device of the class described, the combination with a valve and an alarm mechanism, of a shifting body for conditioning the alarm mechanism to operate, means for retarding the movement of said body, means through which the valve in opening conditions said body to move in one direction, and thereby condition the alarm mechanism to operate, and means whereby the return movement of the valve conditions said body to move in the opposite direction. 19. In automatic sprinkler apparatus, a movable governing body, means for retarding the movement of said body toward its emergency position and for allowing its more rapid movement in moving toward its ineffective position, an emergency mechanism operatively related to said body, actuating means to normally restrain the movement of said body and adapted to operate on the emergency flow of liquid in the connected sprinkler system to allow said body to move toward its emergency position and cause it to condition the emergency mechanism to operate, and to move said body toward its ineffective position when said system is restored to normal condition. 20. In a device of the class described, the combination of a support having a chamber, a fluid body contained in the chamber and adapted to shift therein, means for retarding the shifting of said body, and means controlled by the pressure in the system for shifting said body and causing it to condition the alarm mechanism to operate. 21. In automatic sprinkler apparatus, a movable body, an emergency mechanism operatively related to said body, means to normally restrain the movement of said body and operating under fire emergency conditions to allow the movement of said body toward its emergency position and cause it to condition the emergency mechanism to operate, and operating to effect the movement of said body toward an ineffective position when emergency conditions no longer exist and retarding means for retarding the movement of said body toward its emergency position. 22. In automatic sprinkler alarm apparatus, a water supply pipe for an automatic sprinkler system, a main valve therein, a movable governing body, an alarm mechanism operatively related to said body, an alarm actuating device co-operating with said main valve and normally restraining the movement of said body and under emergency conditions in said system operating to allow the movement of said body toward emergency position and cause it to condition the alarm mechanism to operate, and tending to restore said body to ineffective position when said system is restored to normal conditions and retarding means for retarding the movement of said body toward emergency position and for allowing its more rapid movement in moving toward ineffective position. 23. In a device of the class described, the combination of a support having a chamber, a fluid body contained in said chamber and adapted to shift from place to place therein, means for retarding the shifting of the fluid body, means controlled by the pressure in the system for shifting the fluid body in the chamber, and an electrical

alarm mechanism having terminals in the chamber adapted to be connected and disconnected as the body shifts.

24. In an automatic sprinkler apparatus, 5 a movable governing body, means for retarding the movement of said body toward its emergency position and for allowing its more rapid movement in moving toward its ineffective position, an emergency mechanism operatively related to said body, actuating means comprising an ejector nozzle device adapted to operate on the emergency flow of liquid in the connected sprinkler system to effect the movement of said body 10 toward an emergency position and cause it to condition the emergency mechanism to operate and to effect the movement of said body toward an ineffective position when said system is restored to normal condition.

25. In an automatic sprinkler alarm device, a water supply pipe, a main check valve therein, a coöperating signal actuating mechanism operated by the opening of said valve and comprising an electrical connection and device comprising a mercury seal adapted when displaced to coöperate with said electrical connection.

26. In an automatic sprinkler alarm device, a movable body, means for retarding 30 the movement of said body, an alarm mechanism operatively related to said body and means adapted to be controlled by the pressure in the connected sprinkler system for moving said body and causing it to condition 35 the alarm mechanism to operate and tending to restore said body to ineffective position when said system is restored to normal condition.

27. In an automatic sprinkler alarm device, a movable body, means for retarding the movement of said body toward its emergency position and for allowing its more rapid movement in returning toward its normal ineffective position, an alarm 45 mechanism operatively related to said body, actuating means adapted to be controlled by the flow of liquid in the connected sprinkler system for moving said body into emergency position and causing it to condition 50 the alarm mechanism to operate and allowing said body to return to ineffective position when said system is restored to normal condition.

28. In automatic sprinkler alarm apparatus, a water supply pipe for an automatic sprinkler system, a main automatic valve therein, a movable governing body, an electric alarm mechanism operatively related to said body, an alarm actuating device coöperating with said main valve and operative under emergency conditions in said system to move said body into emergency position and cause it to condition the alarm mechanism to operate, and to tend to restore said 65 body to ineffective position when said sys-

tem is restored to normal conditions and unidirectional retarding means for retarding the movement of said body toward its emergency position and for allowing its comparatively free more rapid movement in 70 returning toward its normal ineffective position.

29. In automatic sprinkler alarm apparatus, a supply pipe for an automatic sprinkler system, a movable governing 75 body, an alarm mechanism operatively related to said body, an alarm actuating device coöperating with and operating under emergency conditions in said system to move said body into emergency position and cause it to condition the alarm mechanism to operate, and to tend to restore said body to ineffective position when said system is restored to normal conditions and unidirectional retarding means for retarding the 80 movement of said body toward its emergency position and for allowing its more rapid movement in returning toward its normal ineffective position.

30. In automatic sprinkler alarm apparatus, an automatic sprinkler system, a movable governing body, an alarm mechanism operatively related to said body, an alarm actuating device coöperating with said system and operating under emergency 95 conditions thereof to move said body into emergency position and cause it to condition the alarm mechanism to operate, and to tend to restore said body to ineffective position when said system is restored to normal conditions and unidirectional retarding means for retarding the movement of said body toward its emergency position and for allowing its comparatively free movement in 100 returning toward its normal ineffective position.

31. In automatic fire alarm apparatus, a movable governing body, an electric alarm mechanism operatively related to said body, an alarm actuating device operating under 11 fire emergency conditions to move said body into emergency position and cause it to condition the alarm mechanism to operate, and to tend to restore said body to ineffective position when emergency conditions no longer exist and unidirectional retarding means for retarding the movement of said body toward its emergency position and for allowing its comparatively free movement in returning 11 toward its normal ineffective position.

32. In automatic sprinkler apparatus, a water supply pipe for an automatic sprinkler system, a main automatic valve coöperating therewith, a movable governing body, an electrically operated emergency mechanism operatively related to said body, an emergency actuating device coöperating with said main valve and operated under emergency conditions in said system to move said body into emergency position and cause 12

it to condition the emergency mechanism to operate, and to allow said body to return to ineffective position when emergency conditions no longer exist and differential retarding means for retarding the movement of said body toward its emergency position and for allowing its more free movement in returning toward its normal ineffective position.

33. In automatic sprinkler alarm apparatus, an automatic sprinkler system, a movable governing body, an alarm mechanism operatively related to said body, an alarm actuating device coöperating with said system and operated under emergency conditions thereof to move said body into emergency position and cause it to condition the alarm mechanism to operate, and to allow said body to return to ineffective position when emergency conditions no longer exist and differential retarding means for retarding the movement of said body toward its emergency position and for allowing its more free movement in returning toward its normal ineffective position.

34. In automatic fire extinguishing apparatus, a movable governing body, an emergency mechanism operatively related to said body, an emergency actuating device operated under fire emergency conditions to move said body into emergency position and cause it to condition the emergency mechanism to operate, and to allow said body to return to ineffective position when emergency conditions no longer exist and differential retarding means for retarding the movement of said body toward its emergency position and for allowing its more free movement in returning toward its normal ineffective position.

35. In automatic alarm apparatus, a movable governing body, an alarm mechanism operatively related to said body, an alarm actuating device operated under emergency conditions to move said body into emergency position and cause it to condition the alarm mechanism to operate, and to allow said body to return to ineffective position when emergency conditions no longer exist and differential retarding means for retarding the movement of said body toward its emergency position and for allowing its more free movement in returning toward its normal ineffective position.

36. In automatic fire alarm apparatus, a movable body, an alarm mechanism operatively related to said body, means operated under fire emergency conditions to move said body into emergency position and cause it to condition the alarm mechanism to operate, and to allow said body to return to ineffective position when emergency conditions no longer exist and retarding means for retarding the movement of said body toward its emergency position.

37. In automatic sprinkler alarm apparatus, a water supply pipe for an automatic sprinkler system, a main valve therein, a movable governing body, an alarm mechanism operatively related to said body, an alarm actuating device coöperating with said main valve and operated under emergency conditions in said system to effect the movement of said body toward emergency position and cause it to condition the alarm mechanism to operate, and to tend to restore said body to ineffective position when said system is restored to normal conditions and retarding means for retarding the movement of said body.

38. In automatic alarm apparatus, a movable governing body, an alarm mechanism operatively related to said body, an alarm actuating device operated under emergency conditions to effect the movement of said body into emergency position and cause it to condition the alarm mechanism to operate, and to effect the return of said body toward its ineffective position when emergency conditions no longer exist and differential retarding means for retarding the movement of said body toward its emergency position and for allowing its more free movement in returning toward its normal ineffective position.

39. In automatic fire alarm apparatus, a movable body, an alarm mechanism operatively related to said body, means operated under fire emergency conditions to effect the movement of said body toward its emergency position and cause it to condition the alarm mechanism to operate, and to effect the movement of said body toward an ineffective position when emergency conditions no longer exist and retarding means for retarding the movement of said body toward its emergency position.

40. In automatic sprinkler apparatus, a water supply pipe for an automatic sprinkler system, a main automatic valve co-operating therewith, a movable governing body, an emergency mechanism operatively related to said body, an emergency actuating device operatively related to said main valve and operating under emergency conditions in said system to move said body toward its emergency position and cause it to condition the emergency mechanism to operate, means to effect the return of said body toward its ineffective position when emergency conditions no longer exist and differential retarding means for retarding the movement of said body toward its emergency position and for allowing its more free movement in returning toward its normal ineffective position.

41. In automatic alarm apparatus, a movable governing body, an alarm mechanism operatively related to said body, an alarm actuating device operating under emergency

- conditions to effect the movement of said body toward its emergency position and cause it to condition the alarm mechanism to operate, means to effect the movement of said body toward an ineffective position when emergency conditions no longer exist and differential retarding means for retarding the movement of said body toward its emergency position and for allowing its more free movement toward an ineffective position.
42. In automatic sprinkler alarm apparatus, a supply pipe for a sprinkler distributing system, a coöperating alarm mechanism adapted to be actuated on the flow of liquid in said supply pipe and comprising differential retarding means for retarding the movement of said alarm mechanism toward an emergency position in which an alarm indication can be given and for allowing the more rapid movement of said alarm mechanism toward an ineffective position to minimize false alarms due to water hammer and so forth.
43. In automatic fire alarm apparatus, a movable governing body adapted to control the action of an alarm mechanism, actuating devices therefor adapted to coöperate with a piping system and effect the actuation of said body on the movement of fluid in said system and differentially acting means for effecting the more rapid movement of said governing body toward an ineffective position than toward an emergency position in which it is adapted to allow an alarm indication to be given to minimize false alarms.
44. In automatic alarm apparatus, a supply pipe for a fire extinguishing system and a coöperating alarm mechanism actuated on discharge of fluid from said system and comprising means for effecting the more rapid movement of said alarm mechanism toward an ineffective position than toward an emergency position in which an alarm indication can be given to thereby minimize false alarms due to water hammer and so forth.
45. In automatic alarm apparatus, a distributing system comprising a supply pipe and automatic sprinkler heads and a coöperating alarm mechanism actuated by movement of fluid in said system and comprising means for effecting the more rapid movement of said alarm mechanism toward an ineffective position than toward an emergency position in which an alarm indication can be given to thereby minimize false alarms due to water hammer and so forth.

In testimony whereof I have signed my name to this specification in the presence of two subscribing witnesses.

EDWARD F. SHIPMAN.
